(57) **CLAIM**

The ornamental design for a detachable foldable hood with attached pouch, as shown and described.

DESCRIPTION

FIG. 1 is a perspective view of a detachable foldable hood with attached pouch;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof;

FIG. 7 is a bottom plan view thereof;

FIG. 8 is a perspective view of the detachable foldable hood with attached pouch in a folded configuration within the pouch;

FIG. 9 is a front elevation view thereof;

FIG. 10 is a rear elevation view thereof;

FIG. 11 is a first side elevation view thereof;

FIG. 12 is a second side elevation view thereof;

FIG. 13 is a top plan view thereof;

FIG. 14 is a bottom plan view thereof; and,

FIG. 15 is an enlarged detail view of the pouch structure taken from FIG. 7.

The broken lines shown in the drawings represent environmental structure only that form no part of the claimed design.
